UNITED STATES PATENT OFFICE.

WILLIAM R. NICHOLS AND CHARLES W. PICKERING, OF PHILADELPHIA, PA.

DESIGN FOR A MEDAL.

Specification forming part of Design No. **7,167**, dated February 10, 1874; application filed January 29, 1874.
[Term of Patent 7 years.]

To all whom it may concern:

Be it known that we, WILLIAM R. NICHOLS and CHARLES W. PICKERING, of Philadelphia, Pennsylvania, have invented a Design for a Centennial Medal, of which the following is a specification:

In the accompanying drawing, Figures 1 and 2 are views of the opposite sides of a medal made in accordance with our design.

On the obverse, Fig. 1, is a view of Independence Hall, as it appeared in 1776, beneath which are the words "Independence Hall, 1776," and above the same, and following the curve of the rim of the medal, is the legend, "Proclaim liberty throughout the land and unto all the people thereof." On the reverse, Fig. 2, is a view of the Memorial Building of the Centennial Anniversary, over which is the title "Centennial Anniversary," the location and date, "Philadelphia, July 4th, 1776," being marked immediately beneath the view of the building.

Any appropriate wording, differing from that above described, may be used in connection with the views of the two buildings,

which are the principal features of the design, and may either be sunken or formed in relief upon the opposite faces of the medal.

We claim—

1. The design for a medal, having upon one side a view of Independence Hall, as described and represented by Fig. 1 of the drawing.
2. The design for a medal, having upon one side a view of the Memorial Building of the Centennial Anniversary, as described and represented by Fig. 2 of the drawing.
3. The design for a centennial medal, having upon one side a view of Independence Hall, and upon the opposite side a view of the Memorial Building of the Centennial Anniversary, all as described and as represented in and by the accompanying drawing.

In testimony whereof we have signed our names to this specification in the presence of two subscribing witnesses.

WILLIAM R. NICHOLS.
CHAS. W. PICKERING.

Witnesses:

WM. A. STEEL,
HARRY SMITH.
